His Attorney.

UNITED STATES PATENT OFFICE

2,582,031

DRAIN MOUNTING AND SEALING
ARRANGEMENTGeorge C. Harbison, Erie, Pa., assignor to General
Electric Company, a corporation of New York

Application January 17, 1947, Serial No. 722,662

4 Claims. (Cl. 182—8)

1

This invention relates to drains and more particularly to an improved arrangement for mounting and sealing liquid drains.

It is an object of this invention to provide an improved arrangement for conducting liquid from the interior to the exterior of a cabinet.

It is another object of this invention to provide an improved drain for conducting liquid from a cabinet and including a liner for the drain adapted to be assembled from the exterior of the cabinet.

It is a further object of this invention to provide a cabinet of the type having spaced inner and outer walls and including an improved arrangement for incorporating a drain in the cabinet and for sealing the drain to the inner and the outer walls.

It is still another object of my invention to provide a drain for a cabinet including a drain tube which can be easily assembled in the cabinet in sealing engagement therewith and which can be easily disassembled therefrom by fastening devices readily accessible from the exterior of the cabinet and from an interior compartment of the cabinet.

In some cabinets liquid, such as moisture condensed from the air in a refrigerator, collects from time to time and it is desirable to dispose of this liquid in some manner. This can be accomplished satisfactorily by providing a drain for conducting the liquid from the interior of the cabinet to the exterior thereof. The problem of disposal of liquid is particularly important in the case of some refrigerator cabinets wherein a food storage compartment is maintained at a relatively high humidity. Under such conditions substantial quantities of condensed moisture may collect during the operation of the refrigerator. The problem of disposing of this water is somewhat complicated by the fact that the space between the inner and outer walls of a refrigerator cabinet is usually filled with heat-insulating material, and any drain passage from the interior of the refrigerator cabinet to the exterior must extend through the intermediate heat-insulating material. Unless adequate provision is made, moisture may leak into the heat-insulating material in the area of the drain passage. The leakage of such moisture is disadvantageous because it tends to reduce the insulating effect of the heat-insulating material and because, moreover, it may result in deterioration of the heat-insulating material. Accordingly, it is another object of my invention to provide a drain for a refrigerator cabinet including an improved arrangement by which the amount of moisture leak-

2

ing into the heat-insulating material in the vicinity of the drain will be minimized.

It is still another object of my invention to provide a drain for a refrigerator cabinet including a seal for minimizing the leakage of moisture into the heat insulating material wherein a portion of the seal is incorporated in a trap for preventing the free circulation of air through the drain.

10 Further objects and advantages of my invention will appear as this description proceeds and the features of novelty which characterize my invention will be pointed out with particularity in the claims annexed to and forming a part of this specification.

For a better understanding of my invention, reference may be had to the accompanying drawing in which Fig. 1 is a sectional view of a portion of a refrigerator cabinet showing an embodiment of the drain; and Fig. 2 is an enlarged sectional view showing details of construction of the drain.

Referring now to Fig. 1, there is illustrated a refrigerator cabinet 1 including an inner wall or liner 2 and an outer wall 3. The space between the inner and outer walls is filled with any suitable heat-insulating material 4. The refrigerator cabinet includes a food storage space 5 and a machinery compartment 6. A door 7 is provided for closing the food storage compartment and a cover 8 is provided for covering the front opening of the machinery compartment. The space between the inner wall 2 and the outer wall 3 at the front of the food storage compartment is closed by a heat-insulating breaker strip 9.

30 During the operation of the refrigerator, moisture may condense from time to time on surfaces within the food storage compartment 5. In order to provide for removal of this liquid, the bottom surface of the food storage compartment is arranged to slope toward a depressed portion 10 located preferably near the rear of the food storage compartment. An opening 11 is provided in this depressed portion and a passage 12 extends from this opening through the heat-insulating material to the machinery compartment 6, passing through an opening provided in a bottom portion 13 of the outer wall 3. The passage 12, therefore, provides a path for the flow of condensed moisture from the food storage compartment to the machinery compartment of the refrigerator. Within the machinery compartment, a receptacle 14 is provided beneath the bottom of the passage 12 to receive the liquid dripping therethrough. The receptacle 14 is supported within the machinery compartment in any

suitable manner, as by brackets, one of which is indicated by 15. The receptacle 14 may be removed for cleaning if desired, but during normal operation of the refrigerator, it is contemplated that any liquid collecting therein will be evaporated into the room by heat developed by the machinery (not shown) in the machinery compartment.

Referring now to the details of the drain as shown in Figs. 1 and 2, it can be seen that the drain passes directly through the heat-insulating material 4 from the inner wall on one side of the heat-insulating material to the outer wall on the other side of the heat-insulating material. Because of the substantially continuous existence of moisture in the area of the drain, there is a tendency for the moisture to leak into the heat-insulating material. In order to minimize leakage of moisture into the heat-insulating material, an arrangement is provided for sealing the drain to the inner wall 2 and to the bottom portion 13 of the outer wall 3. Within the passage 12, a liner or tube 16 of heat-insulating, moisture-impervious material, such as rubber, is provided. The tube 16 includes near its lower end an outwardly-extending portion or flange 17 which is adapted to be brought into sealing engagement with the outer wall. In order to hold this flange 17 in sealing engagement with the outer wall, a ring 18 or member is provided. The ring 18 is pressed against the flange 17 to hold the latter firmly against the outer wall by screws or elements 19, which engage threaded openings in a ring or element 20, which is secured to the outer wall in any suitable manner, as by welding. If desired the screws 19 may engage threaded openings in the outer wall itself, but it is usually more satisfactory to provide an additional part or parts, as the ring 20, on the interior of the wall to provide more durable threaded openings for cooperation with the screws 19. In the construction shown, the flange 17 acts as a gasket to prevent leakage of moisture into the heat-insulating material along the outer wall. Since the flange 17 is integral with the tube 16, this arrangement also effectively prevents the leakage of moisture into the heat-insulating material along the exterior of the tube 16. In order to direct liquid from the passage 12 downwardly upon the sloping sides of a raised portion 21 of the receptacle 14, the lower end of the tube 16 is tapered as indicated at 22. The sloping sides of the raised portion 21 extending above the level of water in the receptacle are provided to minimize the noise which would result from the dripping of water directly into a pool of water.

The tube 16 is provided with a portion 23 of enlarged cross-sectional area near its upper end. An internally threaded nut or coupling element 24 is received within this enlarged portion. In order to provide a seal adjacent the inner wall, the tube 16 includes an inwardly extending portion or flange 25 which fits over the top of the nut 24. In order to hold the portion 25 of the tube in sealing engagement with the depressed portion 10 of the inner wall 2, a second coupling element or threaded collar 26 is provided. The collar 26 is arranged to extend through the opening 11 in the depressed portion 10 of the inner wall and is provided with a flange 27 which overlies the inner wall 2. The collar 26 is threaded exteriorly in order to engage the internally threaded nut 24. As the collar 26 engages the nut 24, the portion 25 of the tube is

pressed into sealing engagement with the inner wall 2, and leakage of moisture into the heat-insulating material in the area of the upper end of the tube 16 is minimized. In order to provide an additional seal and to prevent marring of the surface of the inner wall, a washer 28 is included between the flange 27 and the inner wall.

As can be seen clearly from Fig. 2, the flange 27 of the collar extends a substantial distance 10 above the surface of the depressed portion 10 of the inner wall. The flange 27 supports a cap 29 in such a manner as to form therewith a trap to prevent the free circulation of air between the food storage compartment and the exterior of the refrigerator. This cap 29 includes a central depending guide portion 30 which fits within the collar 26. The cap also includes radial ribs 31 which rest on the top 20 of the collar 26 in order to provide space between the lower surface 32 of the cap and the collar for the passage of liquid draining from the compartment. The cap is provided with a downwardly-extending portion 33 along its outer 25 edge, which extends below the top surface of the collar 26 but is held somewhat above the surface of the depressed portion 10 of the inner wall. By this arrangement a pool of liquid extending to the level of the top of the collar 26 30 is held within the depressed portion 10 of the inner wall and the depending edges of the cap extend into this pool of water to prevent free circulation of air between the food storage compartment and the exterior of the refrigerator.

35 By the arrangement described above the drain tube 16 can readily be inserted after the refrigerator cabinet has been assembled. The tube is inserted through the outer wall upwardly into the drain passage from the machinery compartment and the lower end is then sealed to the outer wall by the screws 19, which are readily accessible. The upper portion of the drain tube is 40 clamped in sealing engagement with the inner wall by means of the collar 26, which is readily accessible from within the food storage compartment. Similarly, should it be desired to remove the drain tube for any reason, as for replacement, the disassembly can be accomplished easily through the above-described fastening 45 devices which are accessible even in the completed cabinet.

While I have described my invention in connection with a particular form of household refrigerator, it will be apparent to those skilled in the art that it can be applied to any apparatus wherein it is desired to prevent leakage of moisture into the area between spaced walls. I intend, therefore, by the appended claims to cover all modifications within the spirit and scope of my invention.

What I claim as new and desire to secure by Letters Patent of the United States is:

1. In combination, an inner wall forming a compartment and having an opening therein, an outer wall spaced from said inner wall and having an opening therein, means including a tube having a flange portion adjacent said outer wall for conducting liquid from said compartment, means including cooperating elements disposed 65 on both sides of said outer wall for maintaining said flange portion in sealing engagement with said outer wall, said tube including a second flange portion adjacent said inner wall, and means readily accessible from within said compartment and including cooperating elements 70

disposed on both sides of said inner wall for maintaining said second flange portion in sealing engagement with said inner wall.

2. In combination, an inner wall forming a compartment and having an opening therein, an outer wall spaced from said inner wall and having an opening therein, means for conducting liquid from said compartment, said means including a tube having a first flange portion, means accessible from the exterior of said outer wall and including cooperating elements disposed on both sides of said outer wall for maintaining said flange portion in sealing engagement with said outer wall, said tube including a second flange portion, a coupling element within said tube adjacent said second flange portion, and a second coupling element accessible from within said compartment for engaging said first coupling element to maintain said second flange portion in sealing engagement with said inner wall.

3. In combination, an inner wall forming a compartment and having an opening therein, an outer wall spaced from said inner wall and having an opening therein, means including a tube having an inwardly extending portion adjacent said inner wall for conducting liquid from said compartment, means readily accessible from within said compartment and including cooperating elements disposed on both sides of said inner wall for maintaining said inwardly extending portion in sealing engagement with said inner wall, said tube including an outwardly extending portion adjacent said outer wall, and means including cooperating elements disposed on both sides of said outer wall for maintaining said outwardly extending portion in sealing engagement with said outer wall.

4. In combination, an inner wall forming a compartment having an opening therein, an

outer wall spaced from said inner wall and having an opening therein, means including a tube receivable through said opening in said outer wall for conducting liquid from said compartment, said tube being of smaller cross-sectional area than the cross-sectional area of said opening in said outer wall, said tube having an inwardly extending flange portion adjacent said inner wall, a coupling element within said tube adjacent said inwardly extending flange portion, a second coupling element accessible from within said compartment for engaging said first coupling element to maintain said inwardly extending flange portion in sealing engagement with said inner wall, said tube including an outwardly extending flange portion adjacent said outer wall, said outwardly extending flange portion extending beyond the edge of said opening in said outer wall, a member engaging said outwardly extending flange portion, and means engaging said member and said outer wall for pressing said outwardly extending flange portion into sealing engagement with said outer wall.
